UNITED STATES PATENT OFFICE.

CHARLES MITCHELL, OF SOUTHAMPTON, ENGLAND; JOHN BUTCHER, ERNEST JOSEPH BURROW, AND ROBERT ERNEST SANDERSON MITCHELL EXECUTORS OF SAID CHARLES MITCHELL, DECEASED.

ANCHOR.

SPECIFICATION forming part of Letters Patent No. 762,242, dated June 7, 1904.

Application filed February 24, 1903. Serial No. 144,917. (No model.)

To all whom it may concern:

Be it known that I, CHARLES MITCHELL, a subject of the King of Great Britain, residing at Fern Lea, Bassett, Southampton, England, have invented certain new and useful Improvements in Anchors, of which the following is a specification, such as will enable those skilled in the art to which it appertains to make and use the same.

10 My invention relates to improvements in anchors for vessels; and it consists of an oscillating head provided with ~~X~~ flukes attached by means of a ball-and-socket connection to the shank of the anchor; and the object of my invention is to provide an anchor of the character described in the use of which the flukes will embed themselves deeply into the earth when a pull is exerted upon the cable attached to the shank; and with these and other objects 15 in view the invention consists in the construction, combination, and arrangement of parts hereinafter described and claimed.

15 The invention is fully disclosed in the following specification, of which the accompanying drawings form a part, in which the separate parts of my improvement are designated by suitable reference characters in each of the views, and in which—

Figure 1 is a perspective view of my anchor. 20 Fig. 2 is a side view showing a part in section; and Fig. 3 is a view looking down upon the flukes, having the shank removed.

In the practice of my invention I provide a shank *a* having a ball formation *a*² upon one end and the other end of which is enlarged and flattened and provided with an eye *a*³, in which the cable is secured.

To the ball *a*² of the shank *a* I attach a member composed of an annular member *b*, having 25 flukes *b*² and a socket-piece *a*⁴, which is secured

to the annular member *b* by means of screws *b*³, and the said member is free to turn on the ball *a*² of the shank *a*, the connection of these points constituting an ordinary ball-and-socket joint. Between the flukes *b*² the annular member is provided with webs *b*⁴, and upon one or more of these flukes I form the eye *c*, which is designed to afford a means for attaching a buoy-rope to said turnable member.

In operation when the anchor reaches the earth the webs between the flukes will penetrate the surface and when a pull is exerted upon the anchor through the attached cable will act as a fulcrum and cause the flukes to be driven farther into the earth, and the member composed of the parts *a*⁴ and *b* will turn upon the ball *a*² of the shank *a*.

In the drawings I have shown a rigid shank composed of one piece; but, if desired, I may make the shank of two pieces joined at the center, so that the sections will fold together.

Having fully described my invention, what I claim as new, and desire to secure by Letters Patent, is—

An anchor of the character described, composed of a shank having a ball formation at one end, an oscillating or turnable head mounted thereon and composed of an annular piece *b* and a socket-piece *a*⁴ secured to said annular piece, said annular piece being provided with flukes *b*², and with webs *b*⁴, substantially as shown and described.

In testimony that I claim the foregoing as my invention I have signed my name in presence of two subscribing witnesses.

CHARLES MITCHELL.
